INVENTOR

J. S. Zerbe

UNITED STATES PATENT OFFICE.

JAMES S. ZERBE, OF CINCINNATI, OHIO.

CLOTHES-SPRINKLER.

SPECIFICATION forming part of Letters Patent No. 233,130, dated October 12, 1880.

Application filed July 22, 1880. (No model.)

To all whom it may concern:

Be it known that I, JAMES S. ZERBE, of Cincinnati, in the county of Hamilton and State of Ohio, have invented a new and useful Improvement in Clothes-Sprinklers, which improvement is fully set forth in the following specification and accompanying drawing, in which a perspective view of the improved sprinkler is shown.

10 The object of this invention is to provide a simple, cheap, and effective clothes-sprinkler; and it consists in a single piece of wire bent centrally into a circle, over which a piece of fine-mesh gauze or wire is placed. The two 15 free ends of the wire are then extended out a sufficient distance and bent back on themselves, terminating in two right-angled extensions over the wire-gauze and provided with a pad, which, after being immersed in water, 20 is caused to act against the wire-gauze below and force the water out from the pad in the form of a spray, as will be hereinafter more fully set forth.

In the drawing, A represents a circle formed 25 of the middle part of a piece of wire, and over this circle a piece of wire-gauze, D, is placed and soldered to the circle. The ends A' of the wire extend out a suitable distance and are then bent back upon themselves, forming 30 a handle, B. The ends thus bent back are turned upwardly and then extended back parallel with the part A' a short distance above

said part. The parts C terminate in two outwardly-projecting angles, C' C', at a point directly above the wire mesh D, and a pad, E, 35 composed of hair or other suitable material, is secured to the ends C' of the pieces C.

In operation, the pad E is immersed in water and held by the hand in the position indicated in Figure 1. By a sudden downward and checking motion the pad E is compelled to strike the gauze D, causing the water to be expelled from the pad and forced through the gauze in the form of spray.

Having described my invention, what I claim 45 as new, and desire to secure by Letters Patent, is—

In a clothes-sprinkler, the wire circle A, formed midway between the ends of a piece of wire and covered with wire-gauze D, extending out a suitable distance, and then bent back, terminating in two outwardly-projecting angles at a point directly above the circle A, in combination with a pad, E, placed on side arms C, substantially as and for the purpose 55 set forth.

In testimony that I claim the above I have hereunto set my hand this 19th day of July, A. D. 1880, in the presence of witnesses.

JAMES S. ZERBE.
